SIGNAL-TRANSLATING CIRCUIT

Harold A. Wheeler, Great Neck, N. Y., assignor
to Hazeltine Corporation, a corporation of
Delaware

Application March 28, 1939, Serial No. 264,525

11 Claims. (Cl. 178—44)

This invention relates to signal-translating circuits and, while of general application, it is of particular utility in the line-scanning output circuits of cathode-ray tube television apparatus.

5 In certain signal-translating systems, it is necessary to transform a signal of any given frequency within a wide range of frequencies or to transform a signal having a wide range of component frequencies, and the transformer circuits utilized for such purposes are frequently such as to produce an undesirable irregularity in the frequency-response characteristic of the system at one or more particular frequencies within the operating range. Further, an undesired transient 15 effect may be caused if the transformed signal comprises a wide range of component frequencies.

Thus, for instance, in a television receiver comprising an electromagnetic scanning circuit, it is desirable to translate a current having a saw-tooth wave form which, in effect, comprises component frequencies of a very wide frequency range. Furthermore, it is frequently desirable to provide the scanning current to the scanning winding of the system from a vacuum tube through a 25 step-down transformer. In such a system, the circuit comprising the scanning winding inherently comprises appreciable shunt capacitance which resonates with the associated circuit inductances and thereby tends to cause irregularities in the 30 frequency-response characteristic of the circuit at one or more particular frequencies with the attendant undesirable effects mentioned above. Also, inherent capacitance coupling the transformer windings of such a system in opposition 35 to their transformer coupling may cause a similar undesirable response but in opposite sense. Similarly, in a television receiver comprising an electrostatic scanning circuit, a step-up transformer is frequently utilized between the last vacuum 40 tube in the scanning-signal translating channel and the scanning plates of the cathode-ray tube. In such a circuit also, capacitance across the output electrode of the tube, as well as the inherent capacitive coupling in opposition to the 45 transformer coupling, may cause undesirable responses similar to those mentioned above.

It is an object of the invention, therefore, to provide a signal-translating circuit of the type under discussion which eliminates one or more of the above-mentioned disadvantages of systems of the prior art.

It is a further object of the invention to provide a signal-translating circuit comprising a step-down transformer for translating scanning currents in a television system utilizing electromagnetic scanning, in which the detrimental effect of capacitance across the scanning windings of the system is substantially eliminated.

It is still another object of the invention to 60 provide a signal-translating circuit comprising

a voltage-changing transformer for translating scanning currents in a television system, in which the detrimental effect of capacitance coupling in opposition to the transformer coupling is substantially eliminated.

In accordance with the invention, a signal-translating circuit for passing a signal comprising a band of frequencies comprises a transformer having closely-coupled primary and secondary windings of substantially different inductances, 10 a terminal circuit connected with the one of the windings of lower inductance, capacitance effectively across the terminal circuit, and capacitance effectively coupling the windings in opposition to their transformer coupling. The 15 capacitances of such a system resonate with resultant inductance of the transformer and of the terminal circuit at a particular frequency within the band and, in accordance with the invention, the capacitances are relatively so proportioned with respect to the inductances of the system as substantially to balance out any irregularity in the coupling characteristic of the translating circuit between said terminal circuit and said winding of greater inductance at frequencies in the vicinity of the said particular frequency of undesired resonance. Either of the above-mentioned capacitances may be comprised, 20 in whole or in part, of inherent circuit capacitance of the signal-translating circuit, or either 25 of the above-mentioned capacitances may be comprised, in whole or in part, of capacitance means added to the circuit to balance out the undesired irregularities in accordance with the invention.

Also in accordance with a preferred embodiment of the invention, the transformer is a step-down transformer utilized to couple a vacuum tube to the scanning windings of a television signal receiver utilizing electromagnetic scanning. 40 In accordance with another preferred embodiment of the invention, the transformer is a step-up transformer utilized to couple a vacuum tube to the scanning plates of a television receiver utilizing electrostatic scanning, preferably by 45 means of a balanced circuit.

As used in this specification, the term "closely-coupled" refers to a coefficient of coupling of a higher order of magnitude than that between air-core transformer windings or radio-frequency transformers wherein the coefficient of coupling usually does not exceed a few per cent. In other words, in a transformer having closely-coupled primary and secondary windings according to this invention, the windings are as close as physical 55 factors will permit and have a coefficient of coupling of not less than 50 per cent and usually more, such as upwards of 90 per cent.

For a better understanding of the invention, together with other and further objects thereof, 60

reference is had to the following specification taken in connection with the accompanying drawing, and its scope will be pointed out in the appended claims.

- 5 Fig. 1 of the drawing is a circuit diagram, partly schematic, of a complete television signal receiver comprising an electromagnetic line-scanning circuit embodying the invention; Fig. 2 is an electrical equivalent circuit diagram of a portion 10 of the scanning-signal translating channel of Fig. 1; Figs. 3a and 3b are characteristic curves utilized to describe certain operating characteristics of the circuit of Fig. 2; Fig. 4 is a modification of the circuit of Fig. 2 utilized for obtaining relationships for proportioning the circuit elements 15 of Fig. 1 in accordance with the invention; Fig. 5a illustrates the load voltage of a prior art system similar to that of Fig. 1; Fig. 5b illustrates the load voltage of the system of Fig. 1; Fig. 6 illustrates a modification of the circuit of Fig. 1 to 20 provide a balanced signal-translating circuit; Fig. 7 illustrates a modification of the signal-translating circuit of Fig. 1 utilizing a transformer comprising separate primary and secondary windings; 25 while Fig. 8 illustrates a modification of the circuit of Fig. 6 as utilized in the scanning-signal translating channel of a television receiver utilizing electrostatic scanning.

Referring now more particularly to Fig. 1 of 30 the drawing, the system there illustrated comprises a television receiver of the superheterodyne type including an antenna system 10, 11 connected to a radio-frequency amplifier 12 to which are connected in cascade, in the order named, an oscillator-modulator 13, an intermediate-frequency amplifier 14, a detector 15, a video-frequency amplifier 16, and an image-reproducing device 17, for example, a cathode-ray receiver tube. A pulse-voltage line-frequency generator 40 18 and a field-frequency generator 19 are coupled to the output circuit of detector 15 and to the sets of deflecting windings 20, 20 and 21, 21, respectively, the line-frequency generator 18 being coupled to line-deflecting windings 20, 20 through 45 a repeated 22, presently to be described. The stages or units 10-19, inclusive, may all be of conventional well-known construction so that detailed illustration and description thereof are deemed unnecessary herein.

50 Referring briefly, however, to the general operation of the system described above, television signals intercepted by antenna circuit 10, 11 are selected and amplified in radio-frequency amplifier 12 and coupled to the oscillator-modulator 13, 55 wherein they are converted into intermediate-frequency signals which, in turn, are selectively amplified in the intermediate-frequency amplifier 14 and delivered to the detector 15. The modulation components of the signal are derived 60 by the detector 15 and the video-frequency signals are supplied to the video-frequency amplifier 16, wherein they are further amplified and from which they are supplied in the usual manner to a brilliancy-control electrode of the image-reproducing device 17. Synchronizing signals are supplied from detector 15 to the control elements of the generators 18 and 19. The intensity of the scanning ray of device 17 is thus modulated or controlled in accordance with the video-frequency 65 70 voltages impressed upon its control electrode in the usual manner. Scanning waves are generated in the line-frequency and field-frequency generators 18, 22, and 19, which are controlled by the synchronizing voltages supplied from detector 15, and applied to the scanning elements

of the image-reproducing device 17 to produce electromagnetic scanning fields, thereby to deflect the scanning ray in two directions normal to each other so as to trace a rectilinear scanning pattern on the screen and to reconstruct the transmitted image.

5 Referring now more particularly to the portion of the system of Fig. 1 embodying the present invention, there is provided a saw-tooth current generator including a vacuum tube 25 coupled to the output circuit of pulse-voltage generator 18. There are included in the output circuit of tube 25 a parallel-connected condenser 26 and resistor 27 effective to develop from the pulse current output of tube 25 a saw-tooth voltage wave, in a 10 manner well understood in the art. This saw-tooth voltage is coupled to the input circuit of a vacuum tube 28 through a coupling condenser 29 in order to provide a saw-tooth current through scanning windings 20, 20 from the output circuit 15 of tube 28, the output circuit of tube 28 being coupled to the scanning windings 20, 20 through a step-down autotransformer including windings 30, 31. The output circuit of vacuum tube 28 may have appreciable inherent capacitances, represented in the drawing by dotted-line condenser 32 across the entire circuit and dotted-line condensers 33 and 34 across the windings 31 and 30, respectively. These inherent capacitances tend to 20 disturb the uniformity of variation of the current through scanning coils 20, 20, which is detrimental during the trace intervals of the scanning cycle. In order to compensate for the effect of capacitance 32, therefore, there is preferably provided an inductance 33 connected in series with resistor 34 and parallel-connected condenser 26 and resistor 27 in the output circuit of vacuum tube 25. 25

30 In considering the characteristic of the circuit 22 of Fig. 1, it will be seen that any inherent capacitance 37 across winding 30 resonates with the associated circuit inductances at a particular frequency and that any inherent capacitance 38 across winding 31 also resonates with the associated circuit inductances at a particular frequency. These two frequencies are, in general, 35 different from each other and from the main resonant frequency of the output circuit of tube 28 as a whole and thereby tend to cause one or more irregularities in the coupling characteristic between generator 18 and scanning windings 20, 20 40 at frequencies at which such irregularities are not corrected by inductance 33 and, therefore, are detrimental. Therefore, in accordance with the invention, either or both of supplemental condensers 39 and 40 are included in the circuit of Fig. 1 in parallel with capacitances 37 and 38, respectively, to balance out any irregularities in the 45 coupling characteristics of the system at frequencies in the vicinity of an undesired resonance. 50

55 Reference is now made to Figs. 2-5b, inclusive, 60 in order to show the manner in which the circuit of Fig. 1 is proportioned in order to balance out such undesired resonance. In Fig. 2 there is shown a circuit which is the electrical equivalent of a portion of the circuit of Fig. 1. The transformer 30, 31 of Fig. 1 may be resolved into the uncoupled inductance components L_a , L_b , and L_m of Fig. 2 in a manner well understood in the art, in which $L_a + L_m$ is the total primary inductance and $L_b + L_m$ is the total secondary inductance. In a closely-coupled transformer, the component L_b may be negative. Windings 20, 20 65 are represented in the circuit of Fig. 2 by the single inductance L_c , while capacitance C_b replaces capacitance 38 and 40 and capacitance 70 75 76

C_m replaces capacitances 37 and 38 of Fig. 1. Capacitance 32 of Fig. 1 is replaced by capacitance C_a in the circuit of Fig. 2.

The general coupling characteristics of the equivalent circuit of Fig. 2 are illustrated by the characteristic curves of Figs. 3a and 3b. Under most conditions, the transformer 30, 31 and its associated inductances and capacitances has a main or fundamental resonant frequency, producing a major peak in the response characteristic, at a frequency f_1 , while the leakage inductance of transformer 30, 31 resonating with the associated circuit capacitances produces a minor peak at a frequency f_2 . The major peak 15 alone is shown by the full-line curve of Fig. 3a and is a response characteristic which may be corrected by the coupling elements 33, 34, 26, and 27 to procure the desired over-all response characteristic from the system. The minor peak 20 X of Fig. 3a is also present if the capacitance C_b in the secondary or low inductance circuit of Fig. 2 is relatively too great. On the other hand, the minor valley Y is present if the capacitance C_m of Fig. 2 is relatively too great. If the 25 primary or high inductance side of the circuit of Fig. 2, that is, the side comprising terminals 3, 4, is connected with an external circuit of very low impedance, the main resonance of the transformer coupling system is destroyed and only the 30 peak or valley caused by the spurious resonance of the leakage inductance remains, this circuit characteristic being illustrated in Fig. 3b. It is, therefore, the purpose of the present invention to proportion the circuit of Fig. 2 in such manner 35 as substantially to eliminate the minor peak X or valley Y.

If the circuit of Fig. 2 is to balance out the above-mentioned undesired irregularity (peak or valley) in the coupling characteristic, it is necessary to obtain the effect of no capacitance current flowing from the junction of capacitances C_m and C_b through either of the inductances L_b and L_c of Fig. 2. That is, equal capacitive currents should flow into the junction of C_m and C_b through one of these capacitances and out through the other. In order to derive an expression for proportioning the circuit of Fig. 2 to meet this condition, it is to be compared with that of Fig. 4 where corresponding elements are given identical reference numerals. The condition set forth above is met if the terminals 1 and 2 of the circuit of Fig. 4 are at the same potential, as driven from terminals 3 and 4, so that no current would flow in a connection between 45 these terminals. The following equations are derived on this basis, in which E_1 represents the voltage across condenser C_a and E_2 represents the voltage across either inductance L_b or condenser C_b under the condition assumed:

$$\frac{E_2}{E_1} = \frac{L_c L_m}{L_a (L_b + L_c) + L_m (L_a + L_b + L_c)} \quad (1)$$

$$\frac{E_2}{E_1} = \frac{C_m}{C_b + C_m} \quad (2)$$

from Equations 1 and 2 the following relation is derived:

$$\frac{C_m}{C_b} = \frac{L_c L_m}{L_a (L_b + L_c) + L_m (L_a + L_b)} \quad (3)$$

A circuit in accordance with that of Fig. 1 and proportioned in accordance with Equation 3 is effective to balance out an undesired irregularity in the coupling characteristics of the system, because the capacitances C_b and C_m , representing condensers 37, 38, 39, and 40 are then

effective merely to supplement the capacitance C_a , or condenser 32, across the entire output circuit of tube 28.

The load voltage across scanning windings 20, 20 of Fig. 1, in a circuit in which the undesired irregularity is not balanced out, is illustrated by the curve of Fig. 5a. The effect of the undesired resonance is to produce a transient in the load voltage, especially during the early part of the trace interval and immediately following the retrace interval. If the circuit of Fig. 1 is proportioned in accordance with Equation 3, however, the load voltage across scanning windings 20, 20 is in accordance with that illustrated by the curve of Fig. 5b, from which, it is seen, the undesired transient has been eliminated. This test may be used for adjusting supplemental condensers 39, 40 to secure the desired balance.

The output circuit of tube 28 of Fig. 1 may be balanced with respect to ground. In Fig. 6 there is illustrated a circuit corresponding to a portion of Fig. 1 comprising such a balanced network. Similar circuit elements are given identical reference numerals in the two figures. The principal change which is made in the circuit of Fig. 6 is that each of the elements 30, 31, and 32 of Fig. 1 has been divided into two elements 30', 31', and 32', respectively, in Fig. 6, the corresponding elements being connected in a balanced relation with respect to winding 31 of the transformer.

Furthermore, it will be understood that, while an autotransformer has been shown in the circuit of Fig. 1, the invention is equally applicable to a circuit comprising a transformer having separate primary and secondary windings, such a circuit being shown in Fig. 7 where corresponding circuit elements have reference numerals identical to those of Fig. 1, except the high inductance transformer primary winding which is indicated at 30'.

It will also be understood that the invention is equally applicable to a circuit comprising a step-up transformer utilized to couple a vacuum tube to the scanning plates of a television receiver utilizing electrostatic scanning. In Fig. 8 there is illustrated a circuit utilized for this purpose, which is otherwise equivalent to that of Fig. 6. The input and output terminals of the circuit of Fig. 6 have been reversed in the circuit of Fig. 8 and the capacitance 32 of Fig. 8 may be comprised, in whole or in part, of the capacitance of the scanning plates 50 of the image-reproducing device 17. Winding 31 of Fig. 8 is coupled to the output terminals of a balanced saw-tooth voltage generator 51 of high impedance and either or both of capacitances 39' and 40 may be comprised, in whole or in part, of the output capacitance of the generator and the inherent capacitance of the transformer. In Fig. 8, there is no inductance corresponding to the scanning inductance L_c of Fig. 2, so the relation of Equation 3 above is simplified by giving L_c an infinite value:

$$\frac{C_m}{C_b} = \frac{L_m}{L_a} \quad (4)$$

This relation is readily adapted to the balanced circuit of Fig. 8. There may be also resistance across the output terminals of the generator, represented by dotted resistor 52 of Fig. 8, and, in such case, balance can be maintained in the circuit by means of resistors 53, 53 coupled respectively across windings 30', 30'. 75

The capacitance 37 and 39 or 37' and 39' in Figs. 1, 6, 7, and 8 provides coupling between the primary and secondary circuits of the transformer which is in opposition to the inductive coupling. By this is meant that the capacitive coupling effect, which varies directly with frequency, tends to cancel the inductive coupling effect at some frequency where the two are equal in magnitude. The opposition between these 10 couplings is inherent in the autotransformers of Figs. 1, 6, and 8. It is obtained in the inductively coupled transformer of Fig. 7 by using a mutual inductance of positive polarity to secure the same effect as in the autotransformer.

15 The lower inductance side 31 of each transformer, together with its directly associated capacitances or other reactance elements, such as the load inductance 20, 20, has a resonant frequency which is usually much higher than the 20 main resonant frequency of the system. It is this spurious resonant frequency, denoted f_3 in Fig. 3, at which the resonance of the lower inductance circuit tends to cause an irregularity in the frequency-response characteristics or a 25 damped transient oscillation. The resonance of this circuit is made ineffective by balancing the circuit capacitances and, if necessary, other impedances in the relations described above. The effect of balancing the capacitances associated 30 with the winding 31 is to nullify the coupling of the transformer at the frequency where this spurious resonance would occur. The coupling is nullified at this frequency by proportioning the coupling capacitance 37, 39 to the proper 35 value in view of the frequency at which the spurious resonance exists. In this way such a resonance is prevented from causing an irregularity in the frequency-response characteristics or a transient oscillation.

40 While there has been described what is at present considered to be the preferred embodiment of this invention, it will be obvious to those skilled in the art that various changes and modifications may be made therein without departing 45 from the invention, and it is, therefore, aimed in the appended claims to cover all such changes and modifications as fall within the true spirit and scope of the invention.

What is claimed is:

50 1. A signal-translating circuit for passing a signal comprising a band of frequencies, said circuit comprising, a transformer having closely-coupled primary and secondary windings of substantially different inductances, a terminal circuit connected with the one of said windings of lower inductance, capacitance effectively across said terminal circuit, and capacitance effectively coupling said windings in opposition to their transformer coupling, said capacitances 55 resonating with the resultant inductance of said transformer at a frequency within said band, at which such resonance is undesired, and said capacitances being relatively so proportioned with respect to said inductances as substantially to balance out any irregularity in the coupling characteristics between said terminal circuit and said winding of greater inductance at frequencies in the vicinity of said frequency of undesired resonance.

70 2. A signal-translating circuit for passing a signal comprising a band of frequencies, said circuit comprising, a transformer having closely-coupled primary and secondary windings of substantially different inductances, a terminal circuit connected with the one of said windings of

lower inductance, capacitance effectively across said terminal circuit, and capacitance effectively coupling said windings in opposition to their transformer coupling, said capacitances resonating with the resultant inductance of said transformer and said terminal circuit at a frequency within said band at which such resonance is undesired, and said capacitances being relatively so proportioned with respect to said inductances as substantially to balance out any irregularity 10 in the coupling characteristics between said terminal circuit and said winding of greater inductance at frequencies in the vicinity of said frequency of undesired resonance.

3. A signal-translating circuit for passing a signal comprising a band of frequencies, said circuit comprising, a transformer having closely-coupled primary and secondary windings of substantially different inductances, a terminal circuit connected with the one of said windings of lower inductance, capacitance consisting at least partially of inherent circuit capacitance effectively across said terminal circuit, and capacitance effectively coupling said windings in opposition to their transformer coupling, said capacitances resonating with the resultant inductance of said transformer and said terminal circuit at a frequency within said band at which such resonance is undesired, and said capacitances being relatively so proportioned with respect to said inductances as substantially to balance out any irregularity 20 in the coupling characteristics between said terminal circuit and said winding of greater inductance at frequencies in the vicinity of said frequency of undesired resonance.

4. A signal-translating circuit for passing a signal comprising a band of frequencies, said circuit comprising, a transformer having closely-coupled primary and secondary windings of substantially different inductances, a terminal circuit connected with the one of said windings of lower inductance, capacitance consisting at least partially of inherent circuit capacitance effectively coupling said windings in opposition to their transformer coupling, said capacitances resonating with the resultant inductance of said transformer and said terminal circuit at a frequency within said band at which such resonance is undesired, and said capacitances being relatively so proportioned with respect to said inductances as substantially to balance out any irregularity 25 in the coupling characteristics between said terminal circuit and said winding of greater inductance at frequencies in the vicinity of said frequency of undesired resonance.

40 5. A signal-translating circuit for passing a signal comprising a band of frequencies, said circuit comprising, a transformer having closely-coupled primary and secondary windings of substantially different inductances, a terminal circuit connected with the one of said windings of lower inductance, capacitance effectively across said terminal circuit, and capacitance consisting at least partially of inherent circuit capacitance effectively coupling said windings in opposition to their transformer coupling, said capacitances resonating with the resultant inductance of said transformer and said terminal circuit at a frequency within said band at which such resonance is undesired, and said capacitances being relatively so proportioned with respect to said inductances as substantially to balance out any irregularity 45 in the coupling characteristics between said terminal circuit and said winding of greater inductance at frequencies in the vicinity of said frequency of undesired resonance.

55 6. A signal-translating circuit for passing a signal comprising a band of frequencies, said circuit comprising, a transformer having closely-coupled primary and secondary windings of substantially different inductances, a terminal circuit connected with the one of said windings of lower inductance, capacitance consisting of inherent circuit capacitance effectively across said terminal circuit, and capacitance consisting of inherent circuit capacitance effectively coupling said windings in opposition to their transformer coupling, said capacitances resonating with the resultant inductance of said transformer and said terminal circuit at a frequency within said band at which such resonance is undesired, and additional capacitance effectively in parallel with one of said first-mentioned capacitances and of such value as substantially to balance out any irregularity 60 in the coupling characteristics between said terminal circuit and said winding of greater inductance at frequencies in the vicinity of said frequency of undesired resonance.

70 7. A signal-translating circuit for passing a signal comprising a band of frequencies, said circuit comprising, a transformer having closely-coupled primary and secondary windings of substantially different inductances, a terminal circuit connected with the one of said windings of

ductance at frequencies in the vicinity of said particular frequency of undesired resonance.

6. A signal-translating circuit for passing a signal comprising a band of frequencies, said circuit comprising, a transformer having closely-coupled primary and secondary windings of substantially different inductances, a terminal circuit connected with the one of said windings of lower inductance, capacitance consisting of inherent circuit capacitance effectively across said terminal circuit, capacitance consisting of inherent circuit capacitance effectively coupling said windings in opposition to their transformer coupling, said capacitances resonating with the resultant inductance of said transformer and said terminal circuit at a frequency within said band at which such resonance is undesired, and additional capacitance effectively in parallel with said capacitance across said terminal circuit and of such value as substantially to balance out any irregularity in the coupling characteristics between said terminal circuit and said winding of greater inductance at frequencies in the vicinity of said particular frequency of undesired resonance.

25 7. A signal-translating circuit for passing a signal comprising a band of frequencies, said circuit comprising, a transformer having closely-coupled primary and secondary windings of substantially different inductances, a terminal circuit connected with the one of said windings of lower inductance, capacitance consisting of inherent circuit capacitance effectively across said terminal circuit, capacitance consisting of inherent circuit capacitance effectively coupling said windings in opposition to their transformer coupling, said capacitances tending to resonate with the resultant inductance of said transformer and said terminal circuit at a frequency within said band at which such resonance is undesired, and additional capacitance effectively in parallel with said capacitance effectively coupling said windings in opposition to their transformer coupling and of such value as substantially to balance out any irregularity in the coupling characteristics between said terminal circuit and said winding of greater inductance at frequencies in the vicinity of said particular frequency of undesired resonance.

45 8. A signal-translating circuit comprising, a transformer having closely-coupled primary and secondary windings of substantially different inductances, said winding of greater inductance having a self-inductance $L_a + L_m$, said winding of less inductance having a self-inductance $L_b + L_m$, and said primary and secondary windings having mutual inductance L_m , a capacitance C_b effectively across said winding of less inductance, and a capacitance C_m effectively coupling said windings in opposition to said transformer coupling, where the circuit parameters are as defined in the specification, said capacitances resonating with the resultant inductance of said transformer and said terminal circuit at a frequency at which such resonance is undesired, said inductances and capacitances being proportioned in accordance with the relation:

$$\frac{C_m}{C_b} = \frac{L_m}{L_a}$$

65 whereby any irregularity in the coupling characteristics between said terminal circuit and said winding of greater inductance at frequencies in

the vicinity of said frequency is substantially balanced out.

9. A signal-translating circuit comprising, a transformer having closely-coupled primary and secondary windings of substantially different inductances, said winding of greater inductance having a self-inductance $L_a + L_m$, said winding of less inductance having a self-inductance $L_b + L_m$, and said primary and secondary windings having mutual inductance L_m , a terminal circuit of inductance L_c connected with said winding of less inductance, a capacitance C_b effectively across said terminal circuit, and a capacitance C_m effectively coupling said windings in opposition to their transformer coupling, where the circuit parameters are as defined in the specification, said capacitances resonating with the resultant inductance of said transformer and said terminal circuit at a frequency at which such resonance is undesired, and said inductances and capacitances being proportioned in accordance with the relation:

$$\frac{C_m}{C_b} = \frac{L_c L_m}{L_a (L_b + L_c) + L_m (L_a + L_b)}$$

25 whereby any irregularity in the coupling characteristics between said terminal circuit and said winding of greater inductance at frequencies in the vicinity of said frequency is substantially balanced out.

30 10. A signal-translating circuit for passing a signal comprising a band of frequencies, said circuit comprising, an autotransformer having a plurality of windings connected in series, a terminal circuit connected with those of said windings that are common to the primary and secondary circuits of the transformer, capacitance effectively in parallel with said terminal circuit, and capacitance effectively in parallel with the others of said windings, said capacitances resonating with the resultant inductance of said transformer and said terminal circuit at a frequency within said band at which such resonance is undesired, and said capacitances being relatively so proportioned with respect to said inductances as substantially to balance out any irregularity in the coupling characteristics between said terminal circuit and said others of said windings at frequencies in the vicinity of said particular frequency of undesired resonance.

35 11. A signal-translating circuit for passing a signal comprising a band of frequencies, said circuit comprising, a transformer having separate but closely-coupled primary and secondary windings of substantially different inductances, a terminal circuit connected with the one of said windings of lower inductance, capacitance effectively across said terminal circuit, and capacitance effectively coupling said windings in opposition to their transformer coupling, said capacitances resonating with the resultant inductance of said transformer and said terminal circuit at a frequency within said band at which such resonance is undesired, and said capacitances being relatively so proportioned with respect to said inductances as substantially to balance out any irregularity in the coupling characteristics between said terminal circuit and said winding of higher inductance at frequencies in the vicinity of said particular frequency of undesired resonance.

HAROLD A. WHEELER.
